(57) **CLAIM**

The ornamental design for a tote shell, as shown and described.

DESCRIPTION

FIG. 1 is a front, elevational view of a tote shell, with the opposite view being identical in appearance;
FIG. 2 is a bottom view of the tote shell of FIG. 1; and,
FIG. 3 is a side view of the tote shell of FIG. 1, with the opposite view being a mirror image.
The elements delineated in dashed lines form no part of the claimed design of the tote shell.
